UNITED STATES PATENT OFFICE.

VICTOR POPP, OF PARIS, FRANCE.

SYSTEM OF GAS-LIGHTING.

SPECIFICATION forming part of Letters Patent No. 283,020, dated August 14, 1883.

Application filed January 10, 1883. (No model.) Patented in France July 18, 1882, No. 159,169, and in Belgium September 12, 1882, No. 59,004.

To all whom it may concern:

Be it known that I, VICTOR POPP, director of the "Compagnie des Horloges Pneumatiques," of Paris, France, have invented a System of Gas-Lighting called "Pneuma-Hydrique Light;" and I do hereby declare that the following is a full, clear, and exact description of the same, reference being had to the annexed sheet of drawings, making a part of this specification; and I further state that I have received Letters Patent of France for said invention for fifteen years, dated July 18, 1882, No. 159,169, and Letters Patent of Belgium for fifteen years, dated September 12, 1882, No. 59,004.

This invention relates to an improved burner of special construction, hereinafter described, whereby an intense and steady light resembling the electric light in whiteness and brilliancy is obtained.

In order that the invention may be more readily understood, I will proceed to describe it with reference to the accompanying drawings, which give several examples of the arrangements of the apparatus.

Figure 1 represents an elevation, and Fig. 2 a central vertical section, of the burner which I employ. Figs. 3 and 4 are horizontal sections taken on lines 1, 2, 3, and 4, Fig. 1, respectively. Fig. 5 is a vertical section of a modified arrangement of burner; and Fig. 6, a horizontal section of the same on line 5 6, Fig. 5.

The same letters of reference indicate the same parts in all the figures.

According to this invention, the supporter of combustion is mixed with the combustible gas before its arrival at the burner, the mixture being effected by leading a tube by which air is supplied at suitable pressure into the gas-supply pipe, whereby the air-current carries the gas along and becomes mixed with it before arriving at the burner.

The burner, which may be readily adapted to existing gas-fittings, is constructed as shown in Figs. 1, 2, 3, 4. It consists of a central tube, *i*, screwing upon the pipe by which the gaseous mixture is supplied. Upon the tube *i* is adjustably screwed a hollow cup, *k*, of

metal or refractory material, which supports 50 a cap, *l*, of fire-clay, of suitable form, according to the intended use of the burner. The flanged base of this thimble-shaped cap *l* is perforated with a ring of holes, *m*, as small and numerous as possible, and the sides of the cap are pierced 55 with oblique perforations *n*. The top of the tube *i* is provided with four small knobs or projections, upon which rests a copper or other cone, *o*, soldered to said tube at a point below the vertical perforations *m* in the base 60 of the refractory thimble *l*. The cone *o* is perforated with small holes, *p*, at its lower end, the sum of whose areas is at least equal to the area of the tube. The refractory thimble *l* is surrounded by an envelope, *g*, of platinum, 65 wire-netting, or fabric, or other refractory material of the same form. The gaseous mixture, arriving by pipe *i*, escapes at the upper orifices, *r*, and passes down against the interior surface of the copper cone *o*, out at orifices 70 *p*, and escapes through the orifices in the cap *l*, at which is burned. The cap is thereby raised to a high temperature, and the platinum-wiresheath, becoming incandescent, radiates the light, the gaseous mixture coming 75 first in contact with the copper cone and then with the refractory cap, becoming raised to an exceedingly high temperature before it is consumed.

The forms and dimensions of the several 80 parts of the burner may be varied and the cone *o* be dispensed with, according to the desired intensity of the light.

In the modified burner represented in Figs. 5 and 6 the metal cone and the fire-clay cap 85 are truncated. The tube *i* is provided with a number of small perforations, *r*, at its upper end, the sum of whose areas is at least equal to the area of the tube, and by which the gaseous mixture is distributed within the chamber *k*. Upon the upper closed end of the tube is fixed a hollow cylinder, *o*, of fire-clay, closed at the lower and open at its upper end. A refractory cap, *l*, surrounds the cylinder *o*, and rests by its base upon cup *k*. This flanged 90 base is perforated with small vertical holes, *m*, and upon it is fixed a platinum-wire cage or envelope, *g*. An annular space, *t*, is left between

l and *o* for the passage of the gaseous mixture, which, on escaping from the orifices *r* in tube *i*, passes over the exterior surface of *o*, whose interior is already heated by the flame, which 5 has not passed through the wire-gauze and has been forced by the pressure of the mixture into the interior of *o*. The gaseous mixture, before passing through the annular space *t*, thus reaches such a temperature that on escaping 10 from this orifice its combustion is greatly promoted.

The compressed air supplied to the gas-supply pipe, as above described, may be made to pass through any suitable pressure-regulator.

I claim—

1. The combination of the air and gas supply pipe *i* with the cup *k*, flanged porous cap *l*, and envelope *g*, of platinum, substantially as herein shown and described.

2. The combination of the air and gas supply pipe *i* with the cup *k*, flanged porous cap *l*, cone *o*, and envelope *g*, of platinum, substantially as herein shown and described.

15

VICTOR POPP.
